CLAIM

I claim the ornamental design for a wall hung toilet, as shown and described.

DESCRIPTION

FIG. 1 is a perspective view of the claimed design; FIG. 2 is a front view of the claimed design shown in FIG. 1;

FIG. 3 is a rear view of the claimed design shown in FIG. 1;

FIG. 4 is a top view of the claimed design shown in FIG. 1; FIG. 5 is a bottom view of the claimed design shown in FIG. 1;

FIG. 6 is a side view of the claimed design shown in FIG. 1; and,

FIG. 7 is a side view of the claimed design shown in FIG. 1.

The ornamental design that is claimed is shown in the drawings as solid lines and surfaces having surface shading. In the drawings, the broken lines depict portions of the wall hung toilet that form no part of the claimed design.
